CABINET FOR A MACHINE FOR MAKING AND FLAKING ICE

Rubin Chaplik and Jesse J. Shelley, Chicago, Ill.

Application May 12, 1955, Serial No. 35,947

Term of patent 14 years

(Cl. D67—3)

Fig. 1

Fig. 1 is a perspective view of a cabinet for a machine for making and flaking ice showing our new design; and Fig. 2 is an enlarged sectional view taken on line 2—2 of Fig. 1.

The opposite side is similar to that shown. The back is plain.

We claim:

The ornamental design for a cabinet for a machine for making and flaking ice, as shown and described.
